UNITED STATES PATENT OFFICE.

WALTER THOMAS, OF YONKERS, NEW YORK, ASSIGNOR TO ALEXANDER SMITH & SONS CARPET COMPANY, OF YONKERS, NEW YORK, A CORPORATION OF NEW YORK.

DESIGN FOR CARPET.

No. 37,675.

Specification for Design.

Patented Nov. 14, 1905.

Application filed October 5, 1905. Serial No. 281,636. Term of patent 3½ years.

To all whom it may concern:

Be it known that I, WALTER THOMAS, of Yonkers, county of Westchester, State of New York, have invented a new, original, and ornamental Design for Carpets, represented in the accompanying drawing.

The figure of the drawing is a plan view of a piece of carpet, showing the design.

I claim—
The ornamental design for a carpet, as shown.

WALTER THOMAS.
